UNITED STATES PATENT OFFICE.

WALTER LANE, OF HOLLAND, MICHIGAN, ASSIGNOR TO BUSH & LANE PIANO CO., OF HOLLAND, MICHIGAN.

UPRIGHT-PIANO FRAME.

1,146,433.

Specification of Letters Patent. Patented July 13, 1915.

Application filed October 30, 1913. Serial No. 798,302.

To all whom it may concern:

Be it known that I, WALTER LANE, a citizen of the United States, residing at Holland, Michigan, have invented certain new and useful Improvements in Upright-Piano Frames, of which the following is a specification.

This invention relates to improvements in upright piano frames.

10 The object of the invention is to improve the construction of piano frames, making a laminated rim of layers of wood glued together supporting the sounding board and the wrest plank at one and the same time, 15 and forming a frame and back for the piano around which the case is built.

Objects which relate to mere details and to economies of construction will definitely appear from the detailed description to 20 follow.

I accomplish the objects of my invention by the devices and means described in the following specification.

The invention is fully defined and pointed 25 out in the claims.

A structure constituting a preferred embodiment of my invention is illustrated in the accompanying drawing, forming a part of this specification in which:

30 Figure I is a detail rear perspective view of a piano embodying the features of my invention, showing the contour and outline of the frame and bracing supports. Fig. II is a front perspective view of the frame, the 35 entire front of the piano being removed, showing details of the string plate. Fig. III is an enlarged detail sectional view on a line corresponding to the line 3—3 of Fig. I, showing in detail the manner in which the 40

filler bar 3' is joined to the frame 3. Fig. IV is an enlarged detail view of the upper left corner of the structure appearing in Fig. I partially in section on a line corresponding to line 4—4 of Fig. V. Fig. V

45 is an enlarged detail sectional view showing the structure of the upper left hand corner of Fig. I taken on a line corresponding to line 5—5 of Figs. I and IV. Fig. VI is an enlarged detail sectional view through the joint between the filler bar 3' and the frame 3, taken on a line corresponding to line 6—6 of Fig. VII. Fig. VII is an enlarged detail sectional view through the joint between the filler bar and the frame, taken

50 on a line corresponding to line 7—7 of Figs.

I and VI. Fig. VIII is an enlarged detail sectional view showing details of construction in the connection of the bar 5 to the right hand portion of the frame appearing in Fig. I, taken on a line corresponding to line 8—8 of Fig. IX. Fig. IX is an enlarged detail sectional view showing the same joint parts taken on a line corresponding to line 9—9 of Figs. I and VIII. Fig. X is an enlarged detail sectional view taken on the irregularly curved line 10—10 of Figs. I and XI showing the details of the joint between the posts and the bars 5, 5'. Fig. XI is a sectional view on a line corresponding to line 11—11 of Fig. X showing further details of the joint between the posts and the bars 5, 5'.

In the drawing similar numerals of reference refer to similar parts throughout the several views.

Considering the reference characters, the piano frame is of the upright design, and the case 1 having the sides 2 is built around said frame. A continuous laminated rim or frame 3, built up of thin layers of wood glued together, extends from the upper bass corner of the wrest plank 7 downwardly to near the bottom edge of the sounding board 16, then curving inwardly along the bottom of the sounding board for about two thirds of the distance, then curving upwardly and outwardly to a point at about two thirds of the height, and then extending along the edge of the sounding board to the top of the wrest plank at the treble end. A filler bar 3' of the same laminated construction is provided at the lower end of the treble side of the sounding board and extends downwardly and inwardly along the edge of the sounding board. This filler bar fills out the general contour of the frame and affords in conjunction therewith extra support for the sounding board, enabling the frame to keep the crown in the sounding board. The upper ends of the sides of this rim or frame 3 are connected by a cross-bar 4 and the wrest plank 7. A brace bar 5, also made of layers of wood glued together extends from the top of the sounding board at the treble side curving upwardly to about two thirds of the distance across the top and then dividing into two branches, one extending slightly up and joining the bass side of the frame 3 just below the lower edge of the wrest plank. The other branch curves downwardly and

joins the side of the frame 3 at a point about half way down, as clearly shown in Fig. I of the drawing. This forms a cut-off and rim support, at the same time allowing a greater area of sounding board and greater freedom of vibration. This bar 5, forms a support for the upper edge of the sounding board, supporting the same free from the wrest plank. This makes a very strong frame with great resonance. Two laminated posts 8 made of glued-up layers of wood are set into this frame for the purpose of bolting the string frame to the same, although with my improved piano frame such posts might be dispensed with by reinforcing the string frame.

The laminated structure which I preferably use consists of alternate layers of maple and walnut. The ends of the filler bar 3' may be joined to the frame 3 by the construction which I will now describe. A similar construction may be made use of at the places where the brace bars 5 and 5' join and where the brace bar 5 joins the frame 3. The end of the filler bar 3' is first shaped so as to engage the periphery of the rim 3 perfectly. Glue is applied to the contacting surfaces of the filler bar 3' and the frame 3, as indicated by the line 19 in Fig. III. This glue holds the parts together, but dowel pins can be used to assist in this. Holes are bored through the frame 3 and the filler bar 3' and large maple dowels 20 are then inserted in these holes, as shown in Fig. III. The ends of these dowels are split and wedges 21 are fitted to the same. The wedges and dowels are thoroughly glued and the wedges are driven into the split ends of the dowel pins, spreading the same. When the glue dries it is impossible to remove the wedges, and the frame having been pressed together with a steel clamp it is impossible to pull this joint apart. I have shown this as a possible construction for the joints referred to above, but other constructions might be very well made use of.

I show the joint at the upper end of the filler bar 3' with the frame 3 in Figs. VI and VII, the same being very similar to the joint at the lower part except that the curve is more abrupt. I show details in construction of the rim 3 and its connection with the brace bar 5 and to the top bar 4 of the frame in Figs. IV and V. The brace bar 5 is gained into the rim as indicated by the dotted lines in Fig. IV and the upper end of the rim is doweled to the top bar 4 of the frame. In this connection I might say where I have shown large maple dowels with wedges in their ends, that screws, bolts or other means might be made use of. These are details which are frequently modified.

In Figs. VIII and IX I show the joint between the brace bar 5 and the right hand part of the rim. The brace bar is gained

into the rim and the joint secured by glue or in any other effective manner. The end of the brace bar 5' is secured to the rim 3 in precisely the same manner, it not being deemed necessary to illustrate that in view of that fact, the brace bar 5' being of the same thickness from front to rear as the bar 5. The brace bars 5, 5' are joined together as indicated in detail in Fig. XI and are gained into the posts 8, 8 as clearly appears in Figs. X and XI. These brace bars are of laminated wood and it will be seen that the whole structure is thus most intimately joined together and a very stanch, strong rim is produced which effectually resists the heavy strain put upon it. This frame is associated with a full metal string plate 6, which is provided with heavy braces 9, 10 and 11, at the treble end, with a scale rib 12 between the same, the braces 10 and 11 being extended downwardly at 10' and 11', below scale rib 12 and connected to the lower part of the string plate. A heavy upright bar 13 is at the treble end and connects to a heavy curved bar portion 14 of the frame which conforms to the lower left hand portion of the frame 3, and is secured thereto by suitable screws 15, 15, as clearly appears from an inspection of Fig. II.

The sounding board 16 is supported in any usual way and has the usual ribs 18 beveled off at 17 toward each end, where they are disposed in suitable gains or otherwise connected to the supporting bars and frame.

I have thus described in detail my improved piano framework structure in the form preferred by me, but as indicated in the description the same can be considerably modified without departing from the spirit of my invention.

Having thus described my invention, what I claim as new and desire to secure by Letters Patent is:

1. An upright piano comprising the combination with a wrest plank and a sounding board, of a laminated frame supporting said wrest plank and said sounding board extending from the top of the bass end of said wrest plank downwardly to the bottom edge of said sounding board, then extending along the bottom edge of the sounding board for about two thirds of the length thereof, then curving upwardly and laterally toward the edge of the sounding board to a point about two thirds of the height thereof, then extending upwardly along the edge of the sounding board and the end of the wrest plank to the top edge of said wrest plank; a laminated filler bar disposed along the edge of the sounding board at the treble end thereof; a laminated brace bar extending from the top of the sounding board at the treble end of the frame for about one half of the distance across the top of said

- sounding board and then extending downwardly and laterally and meeting the main frame at a point about one half the height thereof; and an auxiliary brace bar disposed at the top of the sounding board at the bass end of said frame and connecting the upper end of said main frame with the upper end of said brace bar, all coacting substantially as described for the purpose specified. 55
- 10 2. An upright piano comprising the combination with a wrest plank and a sounding board, of a laminated frame supporting said wrest plank and said sounding board extending from the top of the bass end of said 60
- 15 wrest plank downwardly to the bottom edge of said sounding board, then extending along the bottom edge of the sounding board for about two thirds of the length thereof, then curving upwardly and laterally toward 65
- 20 the edge of the sounding board to a point about two thirds of the height thereof, then extending upwardly along the edge of the sounding board and the end of the wrest 70
- 25 plank to the top edge of said wrest plank, a laminated brace bar extending from the 75
- 30 top of the sounding board at the treble end of the frame for about one half of the distance across the top of said sounding board and then extending downwardly and laterally and meeting the main frame at a point about one half the height thereof, and an auxiliary brace bar disposed at the top of the sounding board at the bass end of said 80
- 35 frame and connecting the upper end of said main frame with the upper end of said brace bar, all coacting substantially as described for the purpose specified. 85
- 40 3. An upright piano comprising the combination with a wrest plank and a sounding board, of a laminated frame supporting said 90
- 45 wrest plank and said sounding board extending from the top of the bass end of said wrest plank downwardly to the bottom edge of said sounding board, then extending along the bottom edge of the sounding board for about two thirds of the length thereof, then curving upwardly and laterally toward 95
- 50 the edge of the sounding board to a point about two thirds of the height thereof, then extending upwardly along the edge of the sounding board and the end of the wrest plank to the top edge of said wrest plank, all coacting substantially as described for the purpose specified.

In witness whereof, I have hereunto set my hand and seal in the presence of two witnesses.
